UNITED STATES PATENT OFFICE.

HARRY HAKE, OF CINCINNATI, OHIO, ASSIGNOR OF ONE-HALF TO RICHARD Y. LUTHY, OF SAME PLACE.

HOLDER FOR MEMORANDUM-BLANKS OR THE LIKE.

SPECIFICATION forming part of Letters Patent No. 661,977, dated November 20, 1900.

Application filed May 15, 1900. Serial No. 16,806. (No model.)

To all whom it may concern:

Be it known that I, HARRY HAKE, a citizen of the United States, residing at Cincinnati, in the county of Hamilton and State of Ohio, have invented a certain new and useful Improvement in Holders for Memorandum-Blanks or the Like, of which the following is a specification.

It is the object of my invention to provide a convenient and ready holder for paper or pads upon which memoranda or notes may be written which is adapted to be readily attached to the side of a desk or in any convenient position for use.

My invention consists in providing a holder for memorandum-blanks and the like simple in construction and operation, capable of attachment to a desk or other convenient position for use, conveniently arranged for being tilted to the desired angle for use and for being folded out of the way, and in the parts and the construction, arrangement, and combinations of parts hereinafter more fully described and claimed.

In the drawings, Figure 1 is a view in perspective showing my improved device attached to a desk, so much of a desk being shown as is necessary to properly illustrate my invention, the device being also shown in various and assumed positions in dotted lines. Fig. 2 is a plan view of my device with a portion broken away to show the depending bottom and side and with the paper or pad clamp in assumed position in dotted lines. Fig. 3 is a left-side elevation of the same. Fig. 4 is a right-side elevation of the holder with the clamp and securing-nut omitted. Fig. 5 is an enlarged section on the line $x-x$ of Fig. 2, showing the device partly broken away and in depending position in dotted lines with the clamp omitted; and Fig. 6 is an enlarged section of the attaching-plate on the line $y-y$ of Fig. 3 with the rod broken away and its ball indicated in dotted lines.

A is an attaching-plate adapted to be secured to a desk, as B, or suitable convenient point for use, as by means of screws taking through holes a . The attaching-plate has secured thereto or integral therewith a socket C, into which a ball D, attached to or integral with a rod E, is adapted to take, forming

a ball-and-socket joint for the purpose hereinafter mentioned. The rod supports a plate F for supporting the blanks, pad, paper, or the like. It preferably has one or more lugs 55 f stamped out of its body and bent backwardly and perforated to form a bearing for the plate about the rod. The plate also preferably has a depending side f' and depending top and bottom $f^2 f^3$ to aid in strengthening the plate. At the side nearest the attaching-plate the plate F has an upwardly-extending side f^4 at either end to form a side rest for the pad or paper. Adjacent to the attaching-plate it has depending extensions f^5 60 f^6 , which may be reinforced by having solder or other brace f^6 take between them and the plate proper. The rod E extends outwardly beyond the plate through an aperture f^7 in its depending side f' , the outer end of the rod being screw-threaded, as at e , to receive a nut e' . Screwing up the nut clamps the plate F on the rod E between the nut and the attaching-plate A by drawing the rod and plate longitudinally of the rod and plane of the supporting-plate in opposite directions, the nut taking against the depending side f' and the depending extensions $f^5 f^6$ taking against the attaching-plate, the ball of the ball-and-socket joint being drawn firmly against the inner 70 walls of the socket at the same time. Before the nut is screwed up, however, the plate F is preferably placed at the desired angle for writing, the plate being pivotally adjustable about the axis of the rod. The holder may be 75 dropped out of the way by loosening the nut, so as to release the firm position of the plate, the rod E dropping into a slot c in the under side of the socket, the slot being of sufficient width to clear the rod and being cut back 80 sufficiently to allow the rod to depend perpendicularly, but retained in operative relation to the attaching-plate by the ball D. The socket in the attaching-plate extends rearwardly to the outer edge of the plate to 85 the full diameter of the ball, as at c' . When it is desired to secure the holder to an object, the rod is first slipped through the attaching-plate and socket and the attaching-plate then secured in position, after which the plate F is 90 slipped over the rod and secured in place. 100

The paper pad or blanks G are held on the

plate F by means of a clamp H. The pad is preferably of the ordinary construction of pads with its top and side adjacent to the attaching-plate glued and with its loose edges 5 at the bottom and outer side, so that when the supporting-plate is dropped the pad may hang with its loose edges at the bottom. This clamp consists, preferably, of a strip h, having an upwardly-extending edge h', adapted 10 to be slipped about the depending top or bottom f² f³, with the depending portion between the parts h and h'. At its upper edge the clamp has a downwardly-projecting lip h², between which and the plate F the paper, 15 pad, or blanks are adapted to be clamped, there being preferably sufficient spring in the clamp to accommodate any reasonable thickness of pad or blanks it is desired to use in the holder. This lip or clamping edge ex- 20 tends parallel with the rod E distant from the longitudinal plane of the axis of the rod.

The holder is arranged so that it may be used either at the left or the right side of a desk or other article. In Fig. 1 it is shown 25 attached to the right of a desk, having the clamp H secured to its upper edge. If it is desired to use the holder as a left-hand holder, the holder is simply turned around, so as to bring its top edge to the bottom, and the 30 clamp H is placed at its other end, which will then be the top, when the holder will be a left-hand holder.

The clamp H has a thumb-piece h³ for its ready manipulation. This thumb-piece may 35 be stamped out of the clamp proper similarly to the lugs f.

The plate may have a recess f⁸ to allow for the socket C. The clamp H may have a sharp edge h⁴, so that the memorandum made may 40 be readily torn from the pad. If desired, the plate may be stamped with suitable perforations or configurations to present a pleasing appearance.

The uses and conveniences of my device 45 may be best described in connection with a roll-top desk. When the desk is open, the blanks or pad in the holder may be used for the purposes of an ordinary scratch-pad for making memoranda, but provides a means 50 for always having the pad in convenient location, where it is always ready for use and in no danger of becoming lost or buried under the papers of a desk. The holder may be adjusted so as to present the most conven- 55 ient angle for writing, as shown in full lines or by dotted lines z, Fig. 1, and when it is desired to place it out of use the nut is relieved and the plate and pad dropped alongside the desk. When the desk is closed, the 60 plate and pad or tablet are again thrown into lateral position at the desired angle and a customer or other person coming to the desk and desiring to communicate with the person having the desk in charge writes his request, 65 memorandum, or instructions on the upper piece of paper in the pad, tears it off, and slips it through the usual opening b in the side of

the desk. The holder may also be secured at any desirable point on the side of the desk— as, for instance, where shown in full lines in Fig. 1 or where shown in dotted lines at w— and may also be placed at the right or left hand of a desk and in either or any position or whether at right or left may be angled as desired and dropped down out of the way, if 75 desired.

My device is exceptionally convenient for the purposes for which it is intended. It is simple and economical in construction and convenient in operation and use.

I claim—

1. In a holder of the character described, the combination of an attaching-plate, a rod extending laterally therefrom, a supporting-plate also extending laterally to the attaching-plate substantially parallel with the rod, a hinge between the attaching-plate and rod, a securing device for exerting pressure on the hinge and supporting-plate in opposite directions substantially longitudinally of the rod and plane of the supporting-plate, means on the supporting-plate extending substantially parallel with the rod laterally to the attaching-plate for receiving a clamp for paper pad and the like and distant from the longitudinal plane of the axis of the rod, with the supporting-plate arranged to swing in lateral position about an axis lateral to the attaching-plate at about the middle of the supporting-plate, with the means for receiving a clamp maintained substantially parallel with and distant from the longitudinal plane of the axis of the rod, and constructed and arranged for permitting the supporting-plate and rod to be dropped out of the way so as to hang from the attaching-plate while the supporting-plate, rod and means for receiving the clamp are maintained substantially parallel, substantially as described.

2. In a holder of the character described, the combination of an attaching-plate, a rod extending laterally therefrom, a supporting-plate also extending laterally to the attaching-plate substantially parallel with the rod, a hinge between the attaching-plate and rod, a securing device for exerting pressure on the hinge and supporting-plate in opposite directions substantially longitudinally of the rod and plane of the supporting-plate, means at both top and bottom of the supporting-plate extending substantially parallel with the rod laterally to the attaching-plate for receiving a clamp for paper pad and the like and distant from the longitudinal plane of the axis of the rod, with the supporting-plate arranged to swing in lateral position about an axis lateral to the attaching-plate at about the middle of the supporting-plate, with the means for receiving a clamp maintained substantially parallel with and distant from the longitudinal plane of the axis of the rod, and constructed and arranged for permitting the supporting-plate and rod to be dropped out of the way so as to hang from the attaching-

plate while the supporting-plate, rod and means for receiving the clamp are maintained substantially parallel, substantially as described.

- 5 3. In a holder of the character described, the combination of an attaching-plate, with a rod and a pivotally-arranged supporting-plate extending laterally therefrom and maintained in substantially parallel planes, a hinge be-
10 tween the attaching-plate and the rod, and a clamp for the supporting-plate and rod constructed and arranged for producing pressure on the hinge and supporting-plate in opposite directions longitudinally of the rod and
15 plane of the supporting-plate and for permitting the supporting-plate and rod to be dropped so as to hang from the attaching-plate, substantially as described.

4. In a holder of the character described, the combination of an attaching-plate, a pivoted supporting-plate extending laterally with relation thereto, a rod for the supporting-plate extending laterally to the attaching-plate substantially parallel to the sup-
20 porting-plate, a hinge between the rod and attaching-plate, and a clamp for the rod for clamping the supporting-plate between the clamp and the attaching-plate by exerting pressure on the supporting-plate and hinge
25 in opposite directions substantially longitudinally of the rod and of the plane of sup-
30 porting-plate, and with the supporting-plate and rod arranged to be dropped out of the way while maintained in substantially parallel position so as to hang from the attaching-plate, substantially as described.

5. In a holder of the character described, the combination of an attaching-plate, a supporting-plate extending laterally with relation thereto, a rod extending laterally from the attaching-plate parallel to the supporting-plate with the supporting-plate pivoted about the rod, and a clamp at the outer end of the rod for clamping the supporting-plate
40 between the clamp and attaching-plate by forcing the supporting-plate and rod in opposite directions longitudinally of the rod and of the plane of the supporting-plate, and

with the supporting-plate and rod arranged to be dropped out of the way while maintain- 50 ing their relatively parallel position so as to hang from the attaching-plate, substantially as described.

6. In a holder of the character described, the combination of an attaching-plate, a piv- 55 oted supporting-plate extending laterally with relation thereto, a rod for the supporting-plate extending laterally from the attaching-plate parallel to the supporting-plate, and a clamp at the outer end of the rod for clamping 60 the supporting-plate between the clamp and attaching-plate by forcing the supporting-plate and rod in opposite directions longitudinally of the rod and of the plane of the sup- 65 porting-plate, and with the supporting-plate and rod arranged to be dropped out of the way while maintaining their relatively parallel position so as to hang from the attaching-plate, substantially as described.

7. In a holder of the character described, 70 the combination of an attaching-plate A, hav-
ing a socket C, and a slot c, a rod E with ball D thereon taking into the socket, a plate F extending longitudinally of and parallel with the rod with the plate swingingly secured 75 with relation to the plate A, depending side f' and depending extensions f'', and nut e' at the outer end of rod E and outside of plate F, constructed and arranged for clamping the plate F between the nut and plate A by 80 forcing the plate F and rod in opposite and parallel directions longitudinally of the rod E and of the plane of the plate F, and with the plate F and rod E arranged to be dropped out of the way while maintaining their rela- 85 tively parallel positions so as to hang from the attaching-plate with the pad side of the plate outward, substantially as described.

In testimony whereof I have signed my name hereto in the presence of two subscriv- 90 ing witnesses.

HARRY HAKE.
